(57) **CLAIM**

(21) Appl. No.: **29/288,687**

We claim the ornamental design for a combined pad holder and tape dispenser, as shown and described.

(22) Filed: **Jun. 18, 2007**

DESCRIPTION

(51) **LOC (8) Cl.** **19-02**

FIG. 1 is front, perspective view of the combined pad holder and tape dispenser of the present invention;

(52) **U.S. Cl.** **D19/65; D19/69**

FIG. 2 is a right side, elevational view of the combined pad holder and tape dispenser shown in FIG. 1;

(58) **Field of Classification Search** D19/67,
D19/69, 78, 75, 77, 89, 65; D3/313; D28/73;
